UNITED STATES PATENT OFFICE.

BENJAMIN GILOWITZ, OF GREENPORT, NEW YORK.

SHOE-SOLE.

1,167,747.

Specification of Letters Patent. Patented Jan. 11, 1916.

Application filed April 22, 1915. Serial No. 23,226.

To all whom it may concern:

Be it known that I, BENJAMIN GILOWITZ, a citizen of Russia, residing at Greenport, in the county of Suffolk and State of New York, have invented certain new and useful Improvements in Shoe-Soles; and I do declare the following to be a full, clear, and exact description of the invention, such as will enable others skilled in the art to which it appertains to make and use the same.

My invention relates broadly to improvements in shoe soles and more particularly to those of the non-slip type.

The main object of the invention is to improve upon the general construction of soles of this character to such an extent as to prevent the stitching or nails securing the same in place, from being torn out, this end being accomplished by provision of properly disposed wear and attaching strips of tough material; additional objects of the invention residing in the provision of means whereby although this attaching and wear strip is presented to pavements and the like, slipping thereof will be prevented, and means whereby such strips, although separable from the soles, will be normally retained in proper position thereon.

With these general objects in view, the invention resides in certain novel features of construction and in unique combinations hereinafter fully described and claimed, several embodiments of the invention being shown in the accompanying drawings wherein like reference characters designate the same parts throughout the several views and wherein:

Figure 1 is a bottom view of one type of the improved sole showing its application to use; Fig. 2 is a central longitudinal section as viewed along the plane indicated by the broken line 2—2 of Fig. 1; Fig. 3 is a vertical transverse section taken on the line 3—3 of Fig. 1; Fig. 4 is a bottom view of an additional form of the invention; Fig. 5 is a vertical transverse section of this form as viewed on the line 5—5 of Fig. 4; Fig. 6 is a bottom view of still another form of the sole; and Fig. 7 is a vertical transverse section thereof as viewed on the plane indicated by the line 7—7 of Fig. 6.

In Figs. 1, 2 and 3, what is commonly termed a half-sole is shown, the numeral 1 designates the non-slip sole proper which is preferably formed of india rubber, although any other preferred type of anti-

slipping material may be used to equal advantage. The sole 1 is channeled on its under side at its outer edge as shown at 2 whereby to provide an integral flange 3 which projects horizontally from the body portion of the sole, said flange being provided with a plurality of spaced and tapered studs 4 which are formed integrally therewith and depend therefrom into the channel 2 as clearly shown in Figs. 2 and 3. These studs are received by openings having tapered walls and formed through an attaching and wear strip 5 of leather or other tough material, said strip being designed on its outer edge to conform to the shape of the outer edge of the sole, while the inner edge of said strip is so shaped as to closely contact with the inner wall of the channel 2, which wall is constituted by the surrounding edge of the body portion of said sole.

It is to be observed that the lower side of the attaching and wear strip 5 is disposed flush with the lower side of the sole, whereby both of these surfaces are exposed to wear when the sole is in ordinary use. It is to be likewise noted, however, that the several anti-slipping studs 4 depend entirely through the openings in the strip 5 and that their lower ends also lie flush with the lower side of said strip. Thus it will be evident that even though the sole, when applied to use, be turned to merely dispose a portion of the strip 5 to the surface upon which the user is walking, the anti-slipping studs 4 will contact with said surface with sufficient friction to prevent slipping. Furthermore, said studs serve as means for effectively connecting the attaching and wear strips 5 to the non-slip sole 1.

When applying the sole constructed as above described to a shoe, whether the latter be new or second-hand, the stitching or nails which are used in the attachment of the sole are passed through the tough attaching and wear strip 5, through the in-turned welt of the shoe, and through the intervening flange 3 and inner sole. Thus it will be evident that all strain which would otherwise be exerted upon the rubber sole, is now imparted to the strip 5 whose qualities are sufficient to withstand the same.

In addition to the features above described, the rear edge of the complete sole is preferably of angular or V-shaped formation as shown at 6 in Fig. 1, the central portion of said rear edge being continued rearwardly

from the ends thereof. By these means, successive bending of the shoe when the user thereof is walking, will have no tendency whatsoever to sever the connections between 5 the rear edge of the improved sole and the permanent sole to which the same is secured. This is deemed a rather novel feature of the invention, since it effectively overcomes the difficulty now encountered by forming half- 10 soles with straight rear edges secured upon transverse lines to the permanent sole of the shoe.

The construction shown in Figs. 4 and 5 is substantially the same as that illustrated 15 in the preceding figures just described. In this form of the invention, however, the body portion of the sole 1^a is of slightly different contour, while the strip 5^a is shown as formed as a part of a complete sole 7. 20 The essential features, however, are incorporated in this form of the invention as shown at 4^a; this character designating the studs which depend through the openings in the strip 5^a from the flange 3^a of the aforesaid body 1^a.

In Figs. 6 and 7 (see more particularly the former) the non-slip sole 1^b is shown constructed to extend throughout the length of the shoe, it being of any desired configuration provided the flange 3^b and the studs 4^b thereon be incorporated. The flange 3^b surrounds the entire sole 1^b as will be evident by an inspection of Fig. 6 and the non-slip studs 4^b depend from said flange through the 35 openings in the surrounding attaching strip 5^b at points spaced substantially equal distances around the sole.

From the foregoing description, taken in

connection with the accompanying drawing, it will be evident that although very simple 40 construction has been provided for the attainment of the desired ends, the complete sole will be very efficient in operation regardless of the form in which it is embodied.

Although soles constructed in accordance 45 with my invention may be applied to use for a number of purposes and upon various styles of shoes, they are particularly adapted for use upon pumps and the like used in fancy dancing, it being evident that slipping of the shoe upon the floor is rendered 50 impossible, as is likewise tearing of the sole from the shoe.

I claim:

1. A non-slip shoe sole having its edge 55 portion reduced in thickness and provided thereon with a plurality of spaced depending non-slip studs, in combination with an attaching and wear strip of tough material underlying said edge portion and having 60 spaced apertures through which said studs project.

2. A non-slip shoe sole having its edge portion channelled on its lower side and 65 equipped with non-slip studs depending into the channel, combined with an attaching and wear strip of tough material received by the channel and having spaced apertures through which said non-slip studs project.

In testimony whereof I have hereunto set 70 my hand in presence of two subscribing witnesses.

BENJAMIN GILOWITZ.
